ASH TRAY OR SIMILAR ARTICLE

Eldon O. McKinney, 210 W. Sunny Dunes Road,
Palm Springs, Calif.

Filed Oct. 8, 1962, Ser. No. 72,011

Term of patent 14 years

(Cl. D85—2)

The side not shown is the same in appearance as the side shown and the back is plain and unornamented.

I claim:

The ornamental design for an ash tray or similar article, substantially as shown and described.
